UNITED STATES PATENT OFFICE.

WILLIAM BOLGER, OF HASTINGS-UPON-HUDSON, NEW YORK.

SAFETY ELECTRIC-CIRCUIT SYSTEM.

1,116,298.

Specification of Letters Patent. Patented Nov. 3, 1914.

Application filed April 24, 1912. Serial No. 234,132.

To all whom it may concern:

Be it known that I, WILLIAM BOLGER, a citizen of the United States, and a resident of Hastings-upon-Hudson, in the county of 5 Westchester and State of New York, have invented a new and Improved Safety Electric-Circuit System, of which the following is a full, clear, and exact description.

This invention relates to safety appliances 10 for automobiles or the like, and has particular reference to the provision of a peculiar arrangement of electric circuit and a movable bolt means for controlling the effect of such circuit or system for various purposes 15 hereinafter more fully set forth.

More specifically stated, I provide a key 20 controlled movable lock bolt having on each end a bridge adapted to connect two adjacent contact springs, each pair of springs 25 being in circuit with a single battery and being associated with any usual or well known ignition controlling switch mounted upon the dashboard, or the like, of the vehicle, whereby, when the vehicle is left by 30 the person in charge in locked condition with the ignition switch open, a stranger attempting to start the vehicle will first turn the switch into operating position, causing the sounding of an audible alarm and without 35 being able to start the engine because of the break in the ignition circuit.

The foregoing and other objects of the invention will hereinafter be more fully described and claimed and illustrated in the 40 drawings forming a part of this specification in which like characters of reference indicate corresponding parts in all the views, and in which—

Figure 1 is a perspective view of the preferred structure of the movable bolt, a portion 45 of the casing therefor being broken away; and Fig. 2 is a diagram of the wiring and several connections above referred to.

The several parts of the device may be 50 made of any suitable materials, and the relative sizes and proportions, as well as the general design of the mechanism, may be varied to a considerable extent without departing from the spirit of the invention hereinafter 55 more fully set forth and specifically claimed.

At 10 I show an internal combustion engine, and at 11 is a battery having connecting wires 12, 13 and 14 connecting the same with the engine.

At 15 is an illustration of a common type 60 of pivoted switch for making or breaking

the ignition circuit just referred to, and 16 is a spark coil in said circuit.

At 17 I show a pair of spaced contact springs to which the wires 13 and 14 are connected. These springs 17 are adapted to be connected electrically by means of a bridge 18 insulated from but carried by a lock bolt 19 when the device is set for operation of the engine. An auxiliary circuit comprises 60 wires 20 and 21 connected to another pair of contact springs 22 normally spaced from each other. The wire 20 is associated with the pivoted switch 15 and makes connection therethrough to the battery when the switch 65 is in operating position, as shown in Fig. 2. At any suitable place in the auxiliary circuit, as, for instance, in the line of the wire 21, is arranged an audible alarm 23 of any suitable character. The contact springs 22 70 are adapted to be connected by a bridge 24 secured through a block of insulation 25 to the bolt 19. The two bridges 18 and 24 may obviously be arranged in many different ways upon the bolt 19, and the bolt likewise may 75 be of any suitable construction and movable in any desired manner. I show, however, for convenience, a sliding bolt operating through a lockcasing 26, the position or movement of the bolt being controlled by 80 means of a key applied at 27, the only exposed portion of the lock mechanism.

The operation may be briefly described as follows: With the parts arranged as shown in Fig. 2 in full lines, the sparking devices 90 will be understood as being active and the engine running, the circuit from the battery being through the switch 15, wire 13, contact 95 17 and bridge 18, and thence through the wire 14 to the engine, the wire 12 being a ground to the engine casing. The circuit through the auxiliary lines will at this time be broken because of the spaced contacts 22. When the motor is stopped, the operator 100 will shift the switch 15 to neutral position 100 and by means of his key will shift the bolt 19 so as to break the contact between the contact springs 17 and close the circuit by means of the bridge 24 between the contacts 22. Any stranger, therefore, attempting 105 to start the motor while the device is set as just described, by turning the switch 15 to operating position, will complete an active circuit through the wires 20 and 21 and alarm 23, causing the alarm to sound. 110

Since the position of the bolt 19, as just described, is such that the contacts 17 are

spaced, such operation of the stranger will be ineffective to start the motor. The alarm will continue sounding until the switch 15 is removed from the normal operating position or until the person in authority shifts the bolt to break the contact at the bridge 24.

The term "battery" as used herein is to be understood as being typical of any suitable source of electrical energy and is not to be interpreted in a limiting sense.

Having thus described my invention, I claim as new and desire to secure by Letters Patent:—

1. The herein described safety system comprising the combination of a battery, a main circuit leading from the battery and including a main switch, said circuit having a pair of spaced contacts, an auxiliary circuit leading from the battery and said main switch and including an audible alarm and a pair of spaced contacts, a member movably relatively to said pairs of contacts, and a pair of connecting members carried by said member adapted to complete the

circuit to said pairs of contacts in alternation. 25

2. The combination of a battery, an ignition switch associated therewith, a main circuit leading from the battery and switch and including a pair of spaced contacts, an auxiliary circuit leading from the battery and ignition switch and including an audible alarm, said auxiliary circuit also including a pair of spaced contacts, and a key controlled lock arranged between the two pairs of spaced contacts, said lock including a slidable bolt and a pair of bridges carried by the bolt adapted to connect the spaced contacts in alternation depending upon the position of the bolt, substantially 40 as set forth.

In testimony whereof I have signed my name to this specification in the presence of two subscribing witnesses.

WILLIAM BOLGER.
